UNITED STATES PATENT OFFICE.

GOTTLOB KLUMPP, OF BAYONNE, NEW JERSEY.

CARPET-CLEANER.

1,063,163.

Specification of Letters Patent. Patented May 27, 1913.

Application filed January 4, 1913. Serial No. 740,171.

To all whom it may concern:

Be it known that I, GOTTLÖB KLUMPP, a citizen of the United States, residing at Bayonne, in the county of Hudson and State 5 of New Jersey, have invented a new and useful Carpet-Cleaner, of which the following is a specification.

This invention relates to carpet sweepers and cleaners, and especially to that class 10 where air forcing apparatus is used to aid the brush in cleaning the carpet; and the objects of my invention are, first, to provide a device of this kind in which a special form of shoe is used to insure the dust and debris 15 being drawn into the cleaner; and, second, to provide a screen of special construction to insure the highest efficiency at all times. In devices of this kind there are two very 20 important features on which the efficiency of the cleaner depends. The first is to get the dust from the floor into the cleaner and at the same time provide means for drawing coarser objects, as pieces of paper, and the like into the dust box; and the other important 25 feature is to have the strainer through which the air passes kept as clean as possible from the collection of dust as otherwise this strainer will become clogged and the efficiency of the cleaner will be impaired.

30 It is the object of my invention to provide a cleaner in which both of these important elements will be of the highest efficiency.

My invention is illustrated in the accompanying drawing, in which—

35 Figure 1, is a vertical section of a part of a carpet cleaner with my improvements applied thereto; Fig. 2, is a plan view of the greater portion of the shoe which I employ, and of a portion of cleaner bottom; Fig. 3, 40 is an elevation of the end of the brush showing its relation with the other parts of the cleaner; and Fig. 4, is a plan view of a section of the strainer.

In the drawing, like numerals of reference 45 refer to the same parts in each of the views.

My improvements are shown in connection with a cleaner comprising a rotatable brush 5, adapted to sweep dirt into a body or dust box 6, having a hinged bottom 7, 50 which may be swung on its hinges to permit of the discharge of dust; bellows 8, mounted above the dust box operable by a link 9, connected with the wheels 10, whereby the bellows may be operated to draw air through 55 the dust box to the bellows through the openings 11, and discharge the same through

the openings 12, in a manner well understood, the cleaner being movable by a handle 13, to operate the various parts.

In order to insure high efficiency in the 60 operation of the parts just described, and especially the air-forcing parts, I provide a special shoe 14, made in one piece, and having a central slot 15, through which the brush 5, is free to make contact with the 65 floor, said shoe having depressed segmental walls on each side of said slot, curved to conform in contour with the brush 5, and lie adjacent thereto in action so that the brush will sweep dirt up either the curved wall, 16, 70 or the wall 17, into the dust receptacle according to the direction in which the sweeper, or cleaner is being moved; and the shoe is provided with ribs 18, and 19, preferably as a continuation of the walls 16, and 17, and 75 adapted to prevent the dirt being thrown out of the dust box after being collected therein. The shoe 14, is suspended through an opening 20, in the bottom 7, of the cleaner by a continuous flexible strip 21, which is pref- 80 erably in one piece, as shown, with the center 22, cut out for the shoe, and the edges tacked to the bottom 7, and cleats 23 within the dust box 6, adapted to make close connection between the bottom 7, and the sides of the 85 dust box; and this strip 21, is secured to the shoe in a manner to prevent air being drawn between the shoe and strip, and is secured to the bottom of the cleaner in the same manner, so that all air drawn into the cleaner 90 by the bellows must come through the opening 15, in the shoe, and the opening 22, in the cloth. Adjusted in this way the shoe will rest upon the floor, and slide along the same in close contact therewith whereby air 95 being drawn into the cleaner by the bellows must come from the floor, or carpet, and when drawn through the carpet, will draw the dust from the carpet with it, as will be understood. As the shoe is supported wholly 100 by the strip 21, it is evident that the curved parts thereof will always be in contact with the floor even if the shoe is very light in weight thereby making it unnecessary to employ springs, or weights to increase the 105 closeness of contact; but I do not limit myself to the weight of the shoe alone in securing close contact with the floor. The advantages of the shoe as shown are that being in one piece there is no chance for 110 leakage of air when the bellows are in operation; and the ease with which the entire shoe

can be held in operative position by a single piece of flexible material.

When the cleaner travels over bits of paper, or light material it is often difficult 5 to prevent the curved sides 16, or 17, driving the paper before the shoe. In order to overcome this difficulty I have provided a plurality of grooves 24, which preferably alternate in the bottoms of the curved parts 16, 10 and 17. In operation the air being drawn through these grooves by the action of the bellows will have the tendency to hold the bits of paper, or other light material to the shoe thereby enabling the shoe to ride over 15 the same until they reach the opening 15, when they will be drawn into the dust box by suction.

While it is important to have a flexibly-mounted shoe that is mounted in an air-tight manner and always in contact with the floor; it is also important to have a strainer cloth always substantially free 20 from dust so that there will be no impediment to the bellows drawing the air through the shoe into the dust box. In order to insure the strainer cloth being as free from dust as possible during the operation of the cleaner I have provided a strainer cloth 25, fastened to the sides of the dust box, and 25 sufficient in size to hang suspended at the center, preferably in contact with the brush 30 5, as shown in Fig. 1; and in order that this cloth may always be in contact with the brush, I have provided small weights, 35 or shot 26, preferably mounted in pockets 27, distributed over the cloth, as particularly shown in Fig. 4. By this arrangement, the rotation of the brush, as well as the jarring of the machine, will cause the 40 cloth 25, to shake, or be agitated whereby any dust having a tendency to lodge on same will be detached and fall back into the dust box since it can not pass out through the opening 15, in the shoe owing 45 to the constant inrush of air caused by the bellows, and can not pass through the strainer cloth. In this way this cloth is always kept clean; and will coat with the shoe to enable the bellows to work perfectly 50 in the cleaner.

In operation, the cleaner may be run in either direction; and as it is put in motion the bellows 8, are also put in motion causing air to flow inward through the opening 55 15, in the shoe and out at the top of the bellows, while the strainer cloth will prevent dust being drawn through. At the same time the brush 5, will be rotated to drive into the cleaner, or dust box thereof, 60 the nap of the carpet, or rug, or the threads

that would not be drawn in by suction alone. As described, all the parts will work together to make a very desirable cleaner.

Having thus described my invention, what I claim as new and desire to secure 65 by Letters Patent of the United States is—

1. In a carpet cleaner, a body having a bottom with an opening therein, a shoe mounted in said opening having a longitudinal slot therethrough and provided with 70 curved sides adjacent thereto, and a flexible strip of material secured to said shoe and the bottom of said cleaner in an air-tight manner and adapted to centralize and flexibly hold said shoe in said opening in a manner 75 to permit the bottom edges of said curved sides to rest on the floor.

2. In a carpet cleaner, a body having a bottom with an opening therein, a shoe mounted in said opening having a longitudinal slot therethrough and provided with 80 curved sides adjacent to said slot, and a flexible strip of material secured to said shoe and the bottom of said cleaner in an air-tight manner and adapted to centralize 85 and flexibly hold said shoe in said opening in a manner to permit the bottom edges of said curved sides to rest on the floor, said bottom edges having longitudinally-spaced transverse grooves, as and for the purpose 90 set forth.

3. In a carpet cleaner having air-forcing apparatus, a body portion having a bottom opening, a shoe adapted to ride upon the floor and having a central, longitudinal slot 95 therein whereby a nozzle is formed, a flexible strip adapted to position said shoe in said opening and prevent the entrance of air around the same, and a rotatable brush in contact with the floor through said slot, 100 as and for the purpose set forth.

4. In a carpet cleaner having air-forcing apparatus, a body portion having a bottom opening, a shoe adapted to ride upon the floor and having a central, longitudinal 105 opening whereby a nozzle is formed, the portions of said shoe adapted to engage the floor being segmental in form and the curved portions ending in ribs rising above the plane of the shoe, a flexible strip adapted to position said shoe in said opening and prevent the flow of air around the same, and a rotatable brush in contact with the floor through said slot, as and for the purpose 110 set forth.

Dated this 19th day of December, 1912.
